CLAIM

The ornamental design for an insert for rolls of towels, as shown and described.

DESCRIPTION

FIG. 1 is a top and side perspective view of an insert for rolls of towels, showing my new design; and,

FIG. 2 is a side elevational view thereof.

The device whose design is claimed is a figure of revolution, and so all side elevational views thereof are identical.

The broken line showing is for illustrative purposes only and forms no part of the claimed design.
